PASTE SUPPLYING APPARATUS FOR GRINDING MACHINES AND THE LIKE

Werner Wrobbel, Nurtingen, Wurttemberg, Germany, assignor to Metabowerk Closs, Rauch & Schnizer K.G., Nurtingen, Wurttemberg, Germany

Filed Oct. 27, 1958, Ser. No. 769,782

Claims priority, application Germany Mar. 4, 1958

21 Claims. (Cl. 51—263)

The present invention relates to grinding and/or polishing machines in general, and more particularly to an improved apparatus for applying a paste-like substance to the periphery of rotating discoid or cylindrical elements which form part of, and are driven by, such machines.

The customary procedure of supplying a grinding or polishing paste to the disks or brushes of grinding or polishing machines is to apply the paste by hand. Such procedure is rather time-consuming and quite uneconomical because the paste is applied in an uneven layer. It has been observed that the time spent and quantities of paste utilized by different workmen operating with identical brushes or disks are widely different. Therefore, the application of paste by hand does not meet the present-day requirements.

Attempts were already made to construct apparatus operated by compressed air for automatically feeding a paste-like substance to the rotating discoid elements of such machines. The disadvantage of apparatus of this type is in that compressed air is seldom available in locations where the grinding or polishing machines are utilized. In addition, the compressed air escaping from such apparatus generates air currents whirling up the dust and dirt which are always present in locations where a grinding or polishing machine is operated. This is particularly undesirable when a polishing operation is performed.

To avoid the just enumerated drawbacks of paste applicators operating with compressed air, such apparatus are often equipped with an electric or like motor and with suitable reducing gearing to feed the paste at a desired rate against the periphery of a revolving discoid or cylindrical element. In addition to the fact that apparatus utilizing electric motors and relatively complicated gearing are rather expensive, they require constant attention and repair, and are too sensitive for use under the conditions attendant to the utilization of grinding and polishing machines.

An additional drawback of known apparatus for applying paste to grinding disks and the like is in that such devices utilize a pivoting bracket or strap which applies pressure to the paste, the latter being customarily in the form of a stick or bar. Such strap necessarily bears only against a single surface of the stick, thus creating the danger of breaking a paste stick especially if the latter is relatively hard and brittle, and hence more likely to break when subjected to one-sided pressures. Still further, a pivoting bracket or strap placed about a paste stick is capable of engaging only a single stick and, after reaching its extreme position, must be returned into its original position when a paste stick is consumed to the extent permitted in such machines. The bracket clearly cannot cause application and consumption of the entire stick so that relatively large discards are left over from each paste stick. Such discards or remnants must be melted and reshaped into new paste sticks or are simply lost for any further use. The losses in time for return-

2

ing the bracket into position for reception of a new paste stick after the preceding one is nearly consumed are considerable, and each insertion of a new stick requires interruption in the operation of a grinding or polishing machine as the operator is unable to operate the machine and replace the paste stick at the same time.

An important object of the present invention is to provide an apparatus for applying paste sticks to the periphery of a rotating discoid or cylindrical element which operates in such manner that the paste sticks may be applied continuously without interruption in operation of the machine of which the rotating element forms a component part.

Another object of the invention is to provide an apparatus of the above described characteristics which is capable of applying paste sticks of different dimensions.

A further object of the invention is to provide an apparatus as above set forth which operates without a motor or compressed air, and in which the rate at which the paste stick is fed against the periphery of a discoid or cylindrical element may be adjusted within a desired range.

A still further object of the invention is to provide an apparatus for applying paste to rotating discoid and/or cylindrical elements of polishing machines and the like which is adjustable in the radial and axial direction of the rotating element.

A yet further object of the invention is to provide an apparatus as above set forth which is so constructed and which operates in such manner that each paste stick is fully consumed before the next one comes into contact with the rotating member.

An additional object of the invention is to provide an assembly as above described which is capable of guiding elongated, short or broken paste sticks into contact with the rotating discoid or cylindrical element.

A concomitant object of the invention is to provide an apparatus for applying paste to rotating elements of grinding and/or polishing machines which is so constructed that the rate at which the paste is fed may be controlled and changed not only before and after but also during the operation of such machines.

A yet further object of the instant invention is to provide an apparatus as above set forth which is fully automatic and requires no attention when the grinding or polishing machine is in actual use.

A yet further object of the invention is to provide an apparatus for applying paste sticks to grinding disks and the like which is so constructed that each major surface of the stick is positively guided during its advance toward the disk.

The above and certain other objects of the invention are attained by the provision of an apparatus which comprises essentially a housing defining a passage substantially radially disposed with respect to the periphery of a rotating discoid element which latter forms a component part and is driven by the motor of the grinding or polishing machine, and means for advancing the paste sticks received in such housing toward and into contact with the periphery of the rotating element. The means for advancing paste sticks comprises at least one but preferably more driven endless chains whose length is so chosen that the next paste stick is positively engaged before the preceding one is fully consumed whereby the next paste stick, while advancing toward the periphery of a rotating disk, cylinder or brush, actually urges the preceding stick toward and into contact with the periphery of the rotating element even though the remaining portion of the preceding stick is already released by the advancing means. In addition, such an arrangement of continuously advancing series of sticks disposed end-to-

end even causes a broken stick to advance in the same manner as the unbroken ones.

The novel features which are considered as characteristic for the invention are set forth in particular in the appended claims. The invention itself, however, both as to its construction and its method of operation, together with additional objects and advantages thereof, will be best understood from the following description of a specific embodiment when read in connection with the accompanying drawings, in which:

Fig. 1 is partly elevational and partly sectional view of the improved apparatus shown attached to the protecting shield of a grinding or polishing disk, the section being taken on line I—I of Fig. 2 as seen in the direction of arrows;

Fig. 2 is top plan view of the structure shown in Fig. 1; and

Figs. 3 and 4 are detail sectional views taken, respectively, on lines III—III and IV—IV of Fig. 2.

Referring now in greater detail to Figs. 1 and 2, the improved paste applicator therein shown is mounted on a support 3 which is fixed to, or integral with, the protecting shield 2 of a grinding or polishing disk or brush 1. The shield 2 is formed with a cutout or aperture 5 through which a grinding or polishing paste stick 4 is led toward and into contact with the periphery 26 of the disk. Support 3 carries or is integral with a pair of spaced guide rails 7 parallel with the axis of drive shaft 6 which latter mounts the grinding or polishing element 1. Each of rails 7 has connected thereto a band or strip 8 at its side facing the elongated rod- or strip-shaped paste 4, the members 8 abutting against the adjacent end surfaces of rollers or runners 9 mounted on an angular carrier 12 for travel along rails 7 between the axial ends of disk 1, the directions in which the carrier 12 travels being indicated by double arrow 11. Carrier 12 has a horizontal leg or extension 13a rotatably supporting the lower end of a threaded spindle 14, and may be fixed in a desired position by means of a retaining element 15, such as a set screw, which is held in support 3 and is adapted to bear against the vertical leg 13b of the carrier to releasably connect the latter with support 3. Screw 15 exerts a horizontal clamping force against leg 13b and, when drawn tight, prevents rollers 9 from traveling along the rails 7 and strips or bands 8 in the axial direction of disk 1.

Carrier 12 supports a special housing or frame 17 for the paste sticks which is adjustable in radial directions of the disk 1. As best shown in Fig. 2, housing or frame 17 is guided by a radial rail 19 which is fixed to carrier 12 and controls a radial rail 18 fixed to the assembly 17.

Housing 17 supports two pairs of endless chains 21 and 22. Stringers 23 of chains 21 and stringers 24 of chains 22 are adjacent to and parallel with each other, their distance a being adjustable and so selected that it corresponds to the thickness, i.e. to the distance between the opposing surfaces, of a preferably rectangular paste strip 4. At least one of chains 21, 22 is driven in the direction of arrows 16 by a mechanism to be described in greater detail hereinafter, the other chains merely traveling with the driven chains or chains due to the engagement of chain links 25 with the paste strip 4. In the illustrated embodiment, chains 21 are driven by a solenoid 35 while the chains 22 merely follow the movement of chains 21 when a paste stick 4 is introduced between stringers 23, 24.

Stringers 23, 24 of respective chain pairs 21, 22 are prevented from yielding to the relatively solid paste sticks by abutting against and by being guided along vertical supporting elements or holding rails 28 which are fixed to housing 17 by means of bolts 27.

As may be seen in Fig. 2, the housing 17 comprises two portions or sections 29a, 29b, the section 29a being movable with respect to the stationary section 29b. In this manner, the housing may accommodate paste sticks of dif-

ferent thicknesses. Housing section 29a is connected with the stationary section 29b by means of spaced spindles 32. The latter are rigidly mounted in section 29b and extend through suitable apertures in section 29a so as to be outwardly adjacent to a U-shaped guide member 31 which guides a pair of opposed surfaces of paste strip 4 passing between chains 21, 22 toward the periphery 26 of disk 1. Each spindle has a threaded end portion receiving an adjusting nut 34. Resilient elements 33, here shown as coil springs, surround the spindles 32 and act between the housing section 29a and nuts 34. Thus, the four major or side surfaces of a generally rectangular paste stick are engaged and guided by member 31 and by the stringers 23, 24 of respective chains 21, 22 within the radial passage defined by housing 17.

Housing section 29b is formed with a horizontal ledge or extension 29b' receiving an internally threaded member 29b'' whose threads mesh with the external threads on spindle 14. In this manner, when the spindle 14 is rotated by an operator who turns the transverse hand-grip member 14a, housing 17 is caused to move toward or away from the periphery 26 depending upon in which direction the spindle rotates. The latter is rotatable in leg 13a without being axially movable therein. Thus, the novel apparatus comprises means consisting of support 3, rails 7, bars 8 and rollers 9 for guiding the carrier 12 and hence the housing 17 in axial directions of the disk 1, as well as means consisting of spindle 14, ledge 29b', member 29b'' and guides 18, 19 for moving and leading the housing 17 with respect to carrier 12 radially toward and away from the periphery 26 while remaining supported by the stationary carrier 12. In addition, by consisting of two relatively movable sections 29a, 29b, composite housing 17 may accommodate paste sticks of different thicknesses a due to the provision of adjusting means 32—34, springs 33 at the same time causing stringers 24 of chain pair 22 to bear against the adjacent surface of a paste stick or sticks with a force sufficient to prevent sliding movements of the sticks when the driven chain pair 21 is idle.

Referring now to Figs. 3 and 4, means for advancing the driven chains 21 therein shown comprises an electrical lifting magnet or solenoid 35 having a slidably armature 36. The lower end of armature 36 which projects beyond the solenoid 35 carries a pivot pin 37 on which is fulcrumed an actuating bar 38. The latter carries a pin 39, parallel with member 37, which is received in an elongated closed slot 41 provided in a lever 43 swingable in the directions of arrow 42. Lever 43 is connected with the cage or housing 44 of a roller- or freewheel-clutch 45 which drives the shaft 46 rigidly mounting the sprockets 47 (see Fig. 1) of driven chains 21. When reciprocated, actuating lever 43 causes intermittent angular movements of clutch 45 and thus advances stringers 23 of driven chains 21 in the direction of arrows 16. The extent of swinging or oscillatory movement of lever 43 is determined by an adjusting or set screw 48 whose end 49 abuts against a stop plate 51 fixed to the portion 29b of housing 17. In this manner, screw 48 also controls the rate at which the paste sticks advance toward the periphery 26 of grinding or polishing disk 1. Plate 51 also supports the lower end 52 of a tension spring 53 whose other end 54 is connected with pivot pin 37 to constantly urge the lever 43 into such extreme position in which the end 49 of adjusting member 48 abuts against the stop 51 and the armature 36 is withdrawn from solenoid 35. The oscillatory movement in opposing direction is performed by lever 43 under the influence of armature 36 when the solenoid 35 mounted on housing section 29b is energized.

The improved paste applying apparatus operates in the following manner:

Carrier 12 and housing 17 are first moved into desired axial position with respect to the periphery 26 by releasing the screw 15 and causing rollers 9 to travel in one of the two directions indicated by arrow 11 along rails 7

of support 3, i.e. in a direction parallel with the axis of shaft 6, whereupon the member 15 is again drawn tight to maintain the assembly 12, 17 in such selected axial position. If necessary, spindle 14 is turned in clockwise or anticlockwise direction to move the housing 17 radially toward (see arrow 16) or away from the periphery 26. It will be noted in Fig. 1 that the housing 17 carries a tubular chute or receptacle 55 which contains at least one but preferably more paste sticks 4' in addition to the paste stick 4 already received in the radial passage of housing 17, i.e. within guide member 31 and between the stringers 23, 24 of respective chain pairs 21, 22. Paste stick 4 is first to come into actual contact with periphery 26. Upon entry of paste stick 4 between stringers 23, 24, nuts 34 are turned in a direction to compress the coil springs 33 on spindles 31 to the extent sufficient to cause satisfactory engagement of said stringers with the adjacent sides of the stick in that the chain links 25 may actually enter to a certain extent into the material of member 4 and insure its advance toward the periphery 26 when at least one set of chains, i.e. chains 21, is driven.

When the electric circuit (not shown) of electromagnet 35 is completed, the latter retracts its armature 36 in upward direction and, over the above-described linkage, causes the lever 43 to turn the clutch 45 in such direction as to cause, over shaft 46 and sprockets 47, a corresponding advance of driven chains 21 in the direction of arrows 16. Such advance of chains 21 causes a corresponding movement of paste stick 4 toward the periphery 26 so that the rotating disk 1 receives a certain amount of paste determined by the frequency of oscillations performed by lever 43 and by the momentary setting of screw 48 which latter, as above described, controls and determines the rate at which the paste stick 4 advances after each retraction of armature 36 into the energized solenoid 35. The other pair of chains 22 merely acts as an abutment for the advancing paste stick 4 and performs intermittent movements similar to those of driven chains 21 without requiring a positive driving connection. It will be understood that the idle or follower chains 22 may be replaced by a solid wall or like guide means along which the paste sticks slide when advanced by the driven chains 21.

When the circuit of solenoid 35 is open resilient member 53 immediately withdraws armature 36 in downward direction until the end 49 of member 48 abuts against the stop plate 51, such movements of armature 36 and hence of lever 43 causing no return movements of stringers 23 in the direction opposed to that of arrows 16 due to the well-known characteristics of clutch 45 which latter transmits rotary motion in one direction only.

When the lowermost paste stick 4 is partly consumed, the end-to-end disposed stick 4' follows immediately by sliding in the enclosure within tubular member 55 toward and into the passage in housing 17; thus, stick 4' is also engaged by stringers 23, 24 of respective chains 21, 22 and is pushed immediately behind member 4 so that the application of paste to the periphery 26 of a grinding or polishing disk 1 need not be interrupted even if the machine of which element 1 forms part is put to extended and uninterrupted use. It will be noted that the length of chains 21, 22 is so selected as to at least approximate the length of a paste stick 4 or 4' whereby the next-following stick 4' is engaged and positively entrained after very small reduction in the length of lowermost member 4. In addition, even small remnants of stick 4 will be completely consumed because the now positively engaged and downwardly advancing paste stick 4' presses the remaining portion of preceding stick 4 toward the periphery 26 even after the remaining portion of member 4 is so small that it is no longer engaged by the stringers 23 and 24.

Completing and opening of the circuit of solenoid 35 may be performed automatically by any suitable means (not shown) or by the operator himself whenever the application of paste to periphery 26 becomes necessary. An

automatic make-and-break system may be utilized when the grinding or polishing machine of which the disk 1 forms part is put to use for relatively long periods of time. It will be understood that the disk 1 may be replaced by a cylinder or a brush without requiring changes in the construction of the paste applying apparatus.

Without further analysis, the foregoing will so fully reveal the gist of the present invention that others can by applying current knowledge readily adapt it for various applications without omitting features that, from the standpoint of prior art, fairly constitute essential characteristics of the generic and specific aspects of this invention and, therefore, such adaptations should and are intended to be comprehended within the meaning and range of equivalence of the following claims.

I claim:

1. An apparatus for applying paste sticks to the periphery of a rotating element in grinding machines and the like which comprises, in combination: a housing defining a passage substantially radially disposed with respect to said periphery for receiving paste sticks in end-to-end relationship; and advancing means supported by said housing for consecutively engaging and moving the paste sticks toward said periphery, said advancing means comprising

10 at least one endless chain having a stringer in contact with at least one paste stick in said passage, and means for so driving the chain that said stringer entrains each paste stick in contact therewith toward said periphery.

2. An apparatus for applying paste sticks to the periphery of a rotating element in grinding machines and the like which comprises, in combination: a housing including a guide member defining a passage substantially radially disposed with respect to said periphery for receiving paste sticks in end-to-end relationship; and advancing

20 means supported by said housing and including a plurality of endless chains each having a stringer adjacent to said guide member and in contact with at least one paste stick in said passage, and means for driving at least one of said chains in such direction that said stringers advance each paste stick in contact therewith toward said periphery.

3. An apparatus for applying paste sticks to the periphery of a rotating element in grinding machines and the like which comprises, in combination: a housing defining a passage substantially radially disposed with respect to said periphery for receiving paste sticks in end-to-end relationship; and advancing means supported by said housing for consecutively engaging and moving the paste sticks toward said periphery, said advancing means comprising

30 at least one endless chain having a stringer in contact with at least one paste stick in said passage, supporting means for holding the stringer in contact with the paste stick, and means for so driving the chain that said stringer entrains each paste stick in contact therewith toward said periphery.

4. An apparatus for applying paste sticks to the periphery of a rotating element in grinding machines and the like which comprises, in combination: a housing defining a passage substantially radially disposed with respect to said periphery for receiving elongated paste sticks of uniform length in end-to-end relationship; and advancing means supported by said housing and including a plurality of endless chains having stringers in contact with at least one paste stick in said passage and of a length corresponding substantially to the length of a paste stick, and means for driving at least one of said chains in such manner that its stringer advances each paste stick in contact therewith toward said periphery.

5. An apparatus for applying paste sticks to the periphery of a rotating element in grinding machines and the like which comprises, in combination: a housing defining a passage substantially radially disposed with respect to said periphery for receiving at least one elongated paste stick; a tubular member connected with said housing and defining an enclosure in continuation of said passage for

receiving paste sticks in end-to-end relationship, one of the paste sticks in said enclosure abutting against the paste stick in said passage; and advancing means supported by said housing and including at least one endless chain having a stringer adjacent to said passage and in contact with the paste stick therein, and means for driving said chain in such manner that the stringer advances each paste stick in contact therewith toward said periphery.

6. An apparatus for applying paste sticks to the periphery of a rotating element in grinding machines and the like which comprises, in combination: a housing defining a passage substantially radially disposed with respect to said periphery for receiving at least one elongated paste stick; a tubular member connected with said housing and defining an enclosure in continuation of said passage for receiving paste sticks in end-to-end relationship, one of the paste sticks in said enclosure abutting against the paste stick in said passage; and advancing means supported by said housing and including a plurality of endless chains each having a stringer adjacent to said passage and in contact with the paste stick therein, and means for driving at least one of said chains in such manner that its stringer advances each paste stick in contact therewith toward said periphery.

7. An apparatus for applying paste sticks to the periphery of a rotating element in grinding machines and the like which comprises, in combination: a housing including a pair of sections one of which is movable toward and away from the other section, said sections defining therebetween a variable passage disposed substantially radially with respect to said periphery and receiving at least one paste stick therein; means for moving said one section toward and away from said other section; and advancing means supported by said housing and comprising at least one driven chain having a stringer adjacent to said passage and engaging with at least one paste stick therein, and drive means operatively connected with said chain for moving the stringer in such direction that each paste stick engaged thereby is fed toward and into contact with said periphery.

8. An apparatus for applying paste sticks to the periphery of a rotating element in grinding machines and the like which comprises, in combination: a housing including a pair of sections one of which is movable toward and away from the other section, said sections defining therebetween a variable passage disposed substantially radially with respect to said periphery and receiving at least one paste stick therein; means for moving said one section toward and away from said other section; resilient means for constantly urging said one section toward said other section; and advancing means supported by said housing and comprising at least one driven chain having a stringer adjacent to said passage and engaging with at least one paste stick therein, and drive means operatively connected with said chain for moving the stringer in such direction that each paste stick engaged thereby is fed toward and into contact with said periphery.

9. An apparatus for applying paste sticks to the periphery of a rotating element in grinding machines and the like which comprises, in combination: a housing including a pair of sections one of which is movable toward and away from the other section, said sections defining therebetween a variable passage disposed substantially radially with respect to said periphery and receiving at least one paste stick therein; a tubular member connected with said housing and defining an enclosure aligned with said passage, said enclosure receiving a plurality of paste sticks in end-to-end relationship, one of the paste sticks in said enclosure abutting against the paste stick in said passage; means for moving said one section toward and away from said other section; and advancing means supported by said housing and comprising at least one driven chain having a stringer adjacent to said passage and engaging with at least one paste stick therein, and drive means opera-

tively connected with said chain for moving the stringer in such direction that each paste stick engaged thereby is fed toward and into contact with said periphery.

10. An apparatus for applying paste sticks to the periphery of a rotating element in grinding machines and the like which comprises, in combination: a housing including a pair of sections one of which is movable toward and away from the other section, said sections defining therebetween a variable passage disposed substantially radially with respect to said periphery and adapted to receive at least one paste stick therein; means for moving said one section toward and away from said other section; resilient means for constantly urging said one section toward said other section; and advancing means comprising at least one chain supported by each of said sections, each of said chains having a stringer adjacent to and in contact with at least one paste stick in said passage, and drive means operatively connected with at least one of said chains for moving same in such direction that the respective stringer advances each paste stick in contact therewith toward said periphery.

11. An apparatus for applying paste sticks to the periphery of a rotating element in grinding machines and the like which comprises, in combination: a housing including a pair of sections one of which is movable toward and away from the other section, said sections defining therebetween a variable passage disposed substantially radially with respect to said periphery and adapted to receive at least one paste stick therein; means for moving said one section toward and away from said other section; resilient means for constantly urging said one section toward said other section; and advancing means comprising a pair of endless chains supported by each of said sections, each of said chains having a stringer adjacent to and in contact with at least one paste stick in said passage, and drive means operatively connected with one pair of said chains for moving same in such direction that the respective stringers advance each paste stick in contact therewith toward said periphery, whereby the stringers of the other pair of said chains are caused by the paste stick in contact therewith to follow the movements of the stringers of said one pair of chains.

12. An apparatus for applying paste sticks to the periphery of a rotating element in grinding machines and the like which comprises, in combination: a housing connected with said machine and including a pair of sections one of which is stationary and the other of which is movable toward and away from said stationary section, said sections defining therebetween a variable vertical passage disposed substantially radially with respect to said element and adapted to receive at least one paste stick therein; means for moving said other section with respect to said one section; resilient means for constantly urging said other section toward said one section; a first pair of endless chains supported by said one section and a second pair of endless chains supported by said other section, each of said chains having a stringer adjacent to and in contact with at least one paste stick in said passage; and means operatively connected with said first pair of chains for moving same in such direction that their stringers advance each paste stick in contact therewith toward said periphery, whereby the stringers of said second pair of chains are caused by the paste stick in contact therewith to follow the movements of the stringers of said first pair of chains.

13. An apparatus for applying paste sticks to the periphery of a rotating element in grinding machines and the like which comprises, in combination: a housing connected with said machine and including a pair of sections one of which is stationary and the other of which is movable toward and away from said stationary section, said sections defining therebetween a variable vertical passage disposed substantially radially with re-

spect to said element and adapted to receive at least one paste stick therein; a vertical tubular member connected to and disposed above said housing, said tubular member defining a vertical enclosure aligned with said passage and adapted to slidably receive therein a plurality of paste sticks in end-to-end relationship whereby the paste sticks in said enclosure descend by gravity toward and into end-to-end contact with the paste sticks in said passage; means for moving said other section with respect to said one section; resilient means for constantly urging said other section toward said one section; a first pair of endless chains supported by said one section and a second pair of endless chains supported by said other section, each of said chains having a stringer adjacent to and in contact with at least one paste stick in said passage; and means operatively connected with said first pair of chains for moving same in such direction that their stringers advance each paste stick in contact therewith toward said periphery, whereby the stringers of said second pair of chains are caused by the paste stick in contact therewith to follow the movements of the stringers of said first pair of chains.

14. An apparatus for applying paste sticks to the periphery of a rotating element in grinding machines and the like which comprises, in combination: a housing defining a passage substantially radially disposed with respect to said periphery for receiving at least one elongated paste stick; a tubular member connected with said housing and defining an enclosure in continuation of said passage for receiving paste sticks in end-to-end relationship, one of the paste sticks in said enclosure abutting against the paste stick in said passage; and advancing means supported by said housing and including at least one endless chain having a stringer adjacent to said passage and in contact with the paste stick therein, and solenoid means for intermittently driving said chain in such manner that the stringer advances each paste stick in contact therewith toward said periphery.

15. An apparatus for applying paste sticks to the periphery of a rotating element in grinding machines and the like which comprises, in combination: a housing defining a passage substantially radially disposed with respect to said periphery for receiving elongated paste sticks of uniform length in end-to-end relationship; and advancing means supported by said housing and including a plurality of endless chains having stringers in contact with at least one paste stick in said passage and of a length corresponding substantially to the length of a paste stick, and means for driving at least one of said chains in such manner that its stringer advances each paste stick in contact therewith toward said periphery, said last mentioned means comprising a lifting magnet supported by said housing and having a reciprocable armature, and an operative connection between said armature and said one chain for moving the latter in response to reciprocating movements of said armature.

16. An apparatus for applying paste sticks to the periphery of a rotating element in grinding machines and the like which comprises, in combination: a housing defining a passage substantially radially disposed with respect to said periphery for receiving at least one paste stick therein; and advancing means including at least one endless chain having a stringer adjacent to and in contact with at least one paste stick in said passage, sprocket means for rotating said chain, shaft means supported by said housing and connected with said sprocket means, magnetic means fixed to said housing and including an armature retractable into and adapted to be withdrawn from said magnetic means, and a linkage for connecting said armature with said shaft means, the linkage rotating said shaft means and said sprocket means for driving said chain in a direction to move each paste stick in contact therewith toward said periphery when said armature is retracted into said magnetic means.

17. An apparatus for applying paste sticks to the pe-

riphery of a rotating element in grinding machines and the like which comprises, in combination: a housing defining a passage substantially radially disposed with respect to said periphery for receiving at least one paste stick therein; and advancing means including at least one endless chain having a stringer adjacent to and in contact with at least one paste stick in said passage, sprocket means for rotating said chain, shaft means supported by said housing and connected with said sprocket means, 5 magnetic means fixed to said housing including an armature retractable into and adapted to be withdrawn from said magnetic means, a linkage for connecting said armature with said shaft means, the linkage rotating said shaft means and said sprocket means for driving said chain in a direction to move each paste stick in contact therewith toward said periphery when said armature is retracted into said magnetic means, and roller clutch means connected with said linkage and with said shaft means for permitting movements of said linkage without rotating said shaft means when the armature is withdrawn from said magnetic means.

18. An apparatus for applying paste sticks to the periphery of a rotating element in grinding machines and the like which comprises, in combination: a housing including a stationary section fixed to said machine and a movable section displaceable toward and away from said stationary section, said sections defining therebetween a passage disposed substantially radially with respect to said periphery and adapted to receive at least one paste stick therein; at least one endless chain supported by said stationary section and having a stringer adjacent to and in contact with at least one paste stick in said passage; sprocket means for said chain; shaft means carried by said stationary section for mounting said sprocket means; 30 a solenoid supported by said stationary section and including an armature retractable into said solenoid when the latter is energized; resilient means for constantly urging said armature into a position in which it is withdrawn from said solenoid; a roller clutch connected with said shaft means and with said armature in such manner as to rotate said sprocket means and to move said stringer in a direction to advance each paste stick in contact therewith toward said periphery when said armature is retracted into said solenoid; and means for adjusting the 35 extent to which said armature is withdrawn from said solenoid.

19. An apparatus for applying paste sticks to the periphery of a rotating element in grinding machines and the like which comprises, in combination: a housing including a stationary section fixed to said machine and a movable section displaceable toward and away from said stationary section, said sections defining therebetween a passage disposed substantially radially with respect to said periphery and adapted to receive at least one paste stick therein; at least one endless chain supported by said stationary section and having a stringer adjacent to and in contact with at least one paste stick in said passage; sprocket means for said chain; shaft means carried by said stationary section for mounting said sprocket means; 50 a solenoid supported by said stationary section and including an armature retractable into said solenoid when the latter is energized; resilient means for constantly urging said armature into a position in which it is withdrawn from said solenoid; and a roller clutch connected with said shaft means and with said armature in such manner as to rotate said sprocket means and to move said stringer in a direction to advance each paste stick in contact therewith toward said periphery when said armature is retracted into said solenoid.

20. For use with a machine of the character described which includes an element rotatable about an axis and having a periphery, and a protecting shield adjacent to said periphery and defining an aperture, an apparatus for applying paste sticks to the periphery of said element comprising, in combination: a support fixed to said shield

adjacent to said aperture; a pair of rails connected with said support and parallel with the axis about which said element rotates; a carrier; roller means connected with said carrier and mounted for travel along said rails; means for releasably connecting said support with said carrier; a radial rail fixed to said carrier; a housing supported by said carrier for movements along said radial rail toward and away from said element, said housing defining a passage substantially radially disposed with respect to said periphery, aligned with said aperture and adapted to receive at least one paste stick therein; means for moving said housing with respect to said carrier; and means for advancing the paste sticks in said passage toward and through said aperture into contact with said periphery, said last mentioned means comprising at least one endless chain supported by said housing and having a stringer adjacent to and in contact with at least one paste stick in said passage, and means for driving said chain in such direction that the stringer advances each paste stick in contact therewith toward said periphery.

21. For use with a machine of the character described which includes an element rotatable about an axis and having a periphery, and a protecting shield adjacent to said periphery and defining an aperture, an apparatus for applying paste sticks to the periphery of said element comprising, in combination: a support fixed to said shield adjacent to said aperture; a pair of rails connected with said support and parallel with the axis about which said

element rotates; a carrier; roller means connected with said carrier and mounted for travel along said rails; means for releasably connecting said support with said carrier; a radial rail fixed to said carrier; a housing supported by said carrier for movements along said radial rail toward and away from said element, said housing defining a passage substantially radially disposed with respect to said periphery, aligned with said aperture and adapted to receive at least one paste stick therein; means for moving said housing with respect to said carrier; and means for advancing the paste sticks in said passage toward and through said aperture into contact with said periphery, said last mentioned means comprising at least one endless chain supported by said housing and having a stringer adjacent to and in contact with at least one paste stick in said passage, means for supporting and maintaining the stringer in contact with the paste stick, and means for driving said chain in such direction that the stringer advances each paste stick in contact therewith toward said periphery.
